(57) **CLAIM**

The ornamental design for a combined hands free phone device and ear piece, as shown and described.

DESCRIPTION

FIG. 1 is a perspective view of a combined hands free phone device and earpiece showing my new design;

FIG. 2 is a top plan view thereof;

FIG. 3 is a bottom plan view thereof;

FIG. 4 is a rear elevation thereof;

FIG. 5 is a front elevation thereof;

FIG. 6 is a side elevation thereof;

FIG. 7 is front perspective view thereof showing the earpiece member removed;

FIG. 8 is a top plan thereof of the hands free phone device only;

FIG. 9 is a bottom plan view of the earpiece member; and, FIG. 10 is a side elevation view thereof, other side opposite being substantially a mirror image.

The broken lines in the figures are for environmental purpose only and form no part of the claimed design.
